UNITED STATES PATENT OFFICE.

ALBERT DE DION AND GEORGES BOUTON, OF PUTEAUX, FRANCE.

APPARATUS FOR REGULATING ELECTRIC GENERATING SYSTEMS.

SPECIFICATION forming part of Letters Patent No. 685,577, dated October 29, 1901.

Application filed June 4, 1901. Serial No. 63,165. (No model.)

To all whom it may concern:

Be it known that we, ALBERT DE DION and GEORGES BOUTON, engineers, citizens of the French Republic, residing at Puteaux, Seine, France, (both having post-office address 24 Quai National, in the said city of Puteaux,) have invented certain new and useful Improvements in Apparatus for Regulating Electric Generating Systems, of which the following is a specification.

This invention relates to internal-combustion engines driving a dynamo-electric machine, and has for its object an arrangement by means of which the speed of the engine is regulated by the dynamo itself, so as to insure a constant difference of potential at its terminals, the said dynamo acting on the eduction-valve of the internal-combustion engine so as to vary its speed according to the intensity of the current to be furnished.

In order that our invention may be clearly understood, we shall describe it with reference to the accompanying drawings, of which—

Figure 1 is a diagrammatical plan view of the general arrangement. Fig. 2 represents, on an enlarged scale, the combination of the solenoid, further termed an "electromagnetic governor," with the device for varying the lift of the eduction-valve stem, as described in Letters Patent granted to us, No. 665,501, dated January 22, 1901.

The motor (shown at R, Fig. 1) of the De Dion and Bouton type drives a dynamo-electric machine *s* of any construction, the main circuit *t* of which has a derived circuit *u*, on which is placed a solenoid, (shown at *n*.) This latter is placed as regards the motor as described above and shown in Fig. 2. The stem *a* of the eduction-valve is actuated by a cam *b* through the medium of a horizontal arm *c*, which is capable of horizontal sliding movement, being mounted on a stud *d*, and caused to slide by a disk *e*, oscillating on an axis *f*. The shape of the said arm *c* is such that according to its position the eduction-valve is more or less raised from its seat, and the speed of the internal-combustion engine varies according to the greater or less quantity of the products of combustion cushioned in the cylinder, as described in Letters Patent granted to us, No. 665,501, dated January 22, 1901. The fluctuations of the volt-

age regulates the speed of the said internal-combustion engines as follows: On the axis *f* of the aforesaid oscillating disk *e* is keyed a pulley *g*, a groove in the periphery of which receives a cord or wire *h*, attached at one end to the core *i* of a solenoid, which we term an "electromagnetic governor." This governor is constituted by a solenoid *j*, a lower disk *k*, and an upper disk or annulus *m*, both of which are connected together by an external casing *n*, surrounding the coils of the solenoid. The core of the solenoid may be constituted by a metal cylinder coned at the lower part and having screwed into its upper end a stem *o* for connecting it to the aforesaid cord or wire *h*. The lower part of the said core is fitted with a cylindrical guiding-rod *p*, capable of sliding in a cylindrical hole *q* provided in the central part of the aforesaid lower disk *k*, which central part may project upward to receive a brass tube *q* and be reversely coned to correspond to the coned lower end of the core. The said core is received in the said brass tube, which contains a cushioning liquid, such as oil, glycerin, or the like.

The solenoid *j* is in a shunt from the dynamo, as shown in Fig. 1. The magnetic lines of force produced by the current flowing through the solenoid run through the aforesaid lower disk *k*, the outer casing *n*, the upper disk or annulus *m*, and the core, the magnetic circuit being thus closed and protected against external action by the said outer casing *n*. The attraction exerted between the core *i* and the lower disk *k* increases as the intensity of the current flowing through the coils of the solenoid increases. The said intensity varies with the voltage of the dynamo, and as the latter voltage tends to increase the core *i* descends in the solenoid and, through the medium of the cord or wire *h* and disk *e*, shifts the arm *c* in the direction of the arrow *r* and reduces the lift of the eduction-valve. The speed of the engine decreases and the dynamo assumes its normal voltage.

Having now particularly described and ascertained the nature of our invention and in what manner the same may be performed, we declare that what we claim is—

In combination with an internal-combus-

tion engine driving a dynamo-electric machine, of a solenoid in shunt from the dynamo, an oscillating disk attached to the core of the solenoid, an induction-valve provided 5 with a stem, a cam, and a horizontally-sliding arm connected with the disk, interposed between the stem and cam and operated by the latter for actuating the former, the whole arrangement being such as to vary the speed 10 of the motor according to the intensity of the

current to be furnished by the dynamo, substantially as set forth.

In testimony whereof we have hereunto set our hands in presence of two subscribing witnesses.

ALBERT DE DION.
GEORGES BOUTON.
